DISPLAY CARTON

John G. Fettinger, Utica, N. Y., assignor to Robert Gair Company, Inc., New York, N. Y., a corporation of Delaware

Application May 13, 1948, Serial No. 146,341

Term of patent 14 years

(Cl. D80—5)

To all whom it may concern:

Be it known that I, John G. Fettinger, a citizen of the United States and a resident of Utica, Oneida County, State of New York, have invented a new, original, and ornamental Design for a Display Carton, of which the following is a specification, reference being had to the accompanying drawing, forming a part thereof, in which the single drawing figure is a perspective view of a display carton showing my new design.

I claim:

The ornamental design for a display carton, as shown.

JOHN G. FETTINGER.
